US00D583816S

(12) **United States Design Patent**
Guccione et al.

(10) **Patent No.:** **US D583,816 S**
(45) **Date of Patent:** **** Dec. 30, 2008**

(54) **WIRELESS TRANSMITTING AND RECEIVING DEVICE**

(75) Inventors: **Darren S. Guccione**, Wheaton, IL (US);
Craig B. Lurey, El Dorado Hills, CA (US)

(73) Assignee: **Callpod Inc.**, Chicago, IL (US)

(**) Term: **14 Years**

(21) Appl. No.: **29/302,117**

(22) Filed: **Jan. 10, 2008**

(51) **LOC (8) Cl.** **14-02**

(52) **U.S. Cl.** **D14/358**

(58) **Field of Classification Search** D14/436, D14/411, 384-385, 518, 348, 432-435, 299, D14/167, 402, 242, 356, 358, 496, 156, 240; 710/300-301; 439/131, 140-141; 361/684, 361/686

(57) **CLAIM**

The ornamental design for a wireless transmitting and receiving device, as shown and described.

DESCRIPTION

FIG. 1 is a front, top perspective view of a wireless transmitting and receiving device;

FIG. 2 is a top view thereof, the bottom being identical thereto;

FIG. 3 is a side view thereof as seen from the left-hand side of FIG. 1;

FIG. 4 is a side view thereof as seen from the right-hand side of FIG. 1

FIG. 5 is a front view thereof;

FIG. 6 is a rear view thereof; and,

FIG. 7 is a rear, top perspective view thereof, shown with a cap exploded for ease of illustration.

The broken lines showing of the circular boundaries in FIGS. 1-2 and 7, the square in FIG. 3, and the USB port in FIG. 7 are for the purpose of illustrating unclaimed portions and form no part of the design.

1 Claim, 1 Drawing Sheet
